UNITED STATES PATENT OFFICE.

HARRY B. JOHNSTON, OF SEATTLE, WASHINGTON.

PISTON AND PISTON-RING.

1,333,023.

Specification of Letters Patent.

Patented Mar. 9, 1920.

Application filed December 12, 1919. Serial No. 344,338.

To all whom it may concern:

Be it known that I, HARRY B. JOHNSTON, a citizen of the United States, residing at Seattle, in the county of King and State of Washington, have invented certain new and useful Improvements in Pistons and Piston-Rings, of which the following is a specification.

This invention relates to improvements in pistons and piston rings and more particularly to that type of piston for use in internal combustion motors; although it is adapted for use in any type of engine where a piston reciprocates within a cylinder and where it is necessary to prevent a fluid from passing from one end of the cylinder to the other, past the piston.

One of the objects of this invention is to provide a piston with an annular groove and a split ring therefor in such proportions and relations that the fluid on one side of the piston will enter the space between the piston and cylinder wall, press upon the ring and force the same along an inclined wall of the piston, against the wall of the cylinder.

Another object is the provision of such a piston and ring construction which when applied to the internal combustion motor will, during the working stroke of the piston, carry the excess oil ahead of the ring, leaving only the thin film thereon which is necessary for proper lubrication. Thus is solved one of the most important problems of the internal combustion motor—that of the prevention of over lubrication.

Still another object is the provision of such a piston and ring construction which will have a tendency to center the piston in the cylinder thus preventing the uneven erosion between the piston and cylinder and obviating the common fault of the ordinary piston which wears the cylinder out of round.

Another and still further object of my invention is the provision of such a piston and ring construction in which not only is there a seal made between the ring and the cylinder wall, but also a tight joint made between the ring and its groove, thus preventing the fluid from leaking around the back of the ring.

All of these objects, I accomplish by providing in the piston body, an annular cir-

cumferential groove and a coöperating ring, 55 the particular form of an embodiment of which is hereinafter set forth.

In the drawings:—

Figure 1 is a cross section of the piston showing the rings in position. 60

Fig. 2 is a cross section of the ring.

Fig. 3 is a plan view of the ring.

The same reference characters refer to similar parts throughout the several figures of the drawing. 65

Referring now particularly to Fig. 1, 10 designates the piston, 11 the groove for the split ring which operates during the working stroke as applied to an internal combustion motor, 12 the groove for the split 70 ring which operates during the suction or intake stroke when applied to an internal combustion motor. In the embodiment of my invention herein disclosed and shown in the accompanying drawings, the two upper 75 and lower side walls of the groove are illustrated as being diverging, with relation to each other, toward the outside of the piston, and one of these walls lies in a plane. The depth of the groove is great enough to permit the insertion of a ring which has a greater radial thickness than axial thickness at its outer periphery, and to leave sufficient depth in addition to allow for a so-called "carbon space." While one of the side walls 80 of the groove is shown as lying in a plane, the essential features in the construction are that the depth of the groove be enough greater than the width of the groove at the periphery of the piston to allow for the 85 ring and carbon space and also that there be an inclined face on which the ring slides in its course toward the cylinder wall. 13 designates the split ring in the groove 11, and 14 the split ring in the groove 12. The 90 rings 13 and 14 are identical in shape.

In the consideration of the construction of the ring, let us consider the ring 13 as exemplary. This ring, as shown, if applied to an internal combustion motor, would be 100 the power stroke ring. As illustrated in this embodiment the ring has upper and lower side walls which diverge toward the outside of the ring, one of which lies in a plane. The height or axial thickness of the ring at the outside thereof is slightly greater than the width of the groove at the periphery of the piston. The same is true at the 105

inner edge of the ring as compared with the inner or bottom width of the groove. The surfaces of the rings, as shown, however, have the same angle with relation to the axis of the piston as the angle of the corresponding part in the groove.

The upper surface 15 of the ring is the surface upon which the gas or other fluid acts and its coöperation with its adjacent 10 groove wall is not so important as the co-operation between the other inclined wall 16 and its corresponding groove wall.

An important feature of the construction of my ring is that its radial thickness is 15 greater than its axial thickness at its periphery. The advantage of this construction will be hereinafter brought out.

The result of this construction of the ring is that when the ring is installed in the groove, 20 it extends beyond the peripheral surface of the piston and also leaves a carbon space 19 at the inside of the ring and the bottom of the groove, as clearly shown in Fig. 1. One of the purposes of this construction is to 25 permit free access of the gas to the top of the ring between the wall of the cylinder and the piston, and thus force the ring outward against the wall of the cylinder. The purpose of the so-called "carbon space" 19 is 30 to prevent clogging of the ring with carbon and also to furnish a space for oil.

I find that a piston and ring constructed as above set forth renders an internal combustion motor very efficient and I believe the 35 reasons to be as follows:

As the gas from the combustion chamber passes down the side of the piston, it comes in contact with the upper surface 15 of the ring 13 and somewhat with the outer surface 40 17. Since the area of the surface 15 is much greater than the area of the surface 17, the result is that the ring is pushed along the inclined side of the groove on its face 16 and against the wall of the cylinder. Another 45 condition which I find is brought about is the proper sealing between the surface 16 of the ring and its bearing surface in the groove. This prevents the escape of gas underneath the ring which could not be avoided with a shallow groove and corresponding radially thin ring.

I have also found that in an internal combustion motor equipped with my invention the action of the gas forces the ring against 55 the cylinder wall during the working stroke in such a way as to remove the excess oil from the cylinder, leaving only a sufficient quantity to properly lubricate the engine without permitting excess oil to pass into the combustion chamber thereby causing 60 fouling of the walls thereof and of the spark plug, valves, etc.

I have found further that in an internal combustion motor equipped with my invention, there is not the tendency for the cylin-

ders to be worn out of round. This is due to the fact that during the working stroke, the piston is held centered by the action of the ring on the inclined wall of the piston. This is in effect a hollow cone, (the ring) holding within itself a solid cone (the inclined wall of the groove). In this way the piston is held centered and excess wear is prevented between the piston and cylinder wall.

The ring of my invention is not solid but 75 is split as shown at 18. In the drawings I have illustrated my preferred embodiment wherein the ring has one split. I desire to have it understood, however, that the split shown is merely illustrative, and the invention is not limited to a ring having a single split, since I have found that very efficient results are obtained by my invention having more than one split in the ring. Neither do I limit myself to the right angular split 80 shown by the drawing since any well known or suitably shaped split can be used.

I have discovered that with my invention applied to an internal combustion motor, the amount of oil supplied to the working 90 surfaces of the rings can be controlled by the width of the split in the ring.

In the herein described embodiment of my invention, I have shown two rings but it is to be understood that any desired number 95 may be used.

In this invention the resiliency of the ring is not wholly depended upon to expand the ring as is common in the art, since the correlation and shape of the parts are such 100 that the force of the gas expands the ring and efficiently seals the space between the piston and wall of the cylinder.

I have found that an internal combustion motor equipped with my invention has such 105 compression that it is unnecessary to furnish an over-supply of gasoline in starting the motor. This does away with a fault very common in gasoline motors since when an excess of gasoline is present in the combustion chamber, the lubricating oil is washed away by the gasoline with a consequent scoring 110 of the wall of the cylinder.

In the drawings it is to be noted that the 115 rings are shown large relatively to the size of the piston. This is done in order to more clearly show the relative proportions of the dimensions of the ring and also of the groove and is not to be taken as a limitation since rings very much smaller may be used 120 as long as the relative proportions of the dimensions are maintained as herein described.

In my preferred form of piston, I construct the part nearest the combustion chamber as at 20 of less diameter than the part 125 farthest away from the combustion chamber, as at 21. The purpose of this construction is to permit more clearance above the power stroke ring to allow the gas to reach the ring quite freely to force the same against the 130

wall of the cylinder during the working stroke, while still steadyng the lower or crank end of the piston.

It is obvious that many minor changes in 5 the construction and arrangement of the rings on the piston may be made without departing from the spirit of the claims.

This case is a division, in part, of my co-pending application Serial No. 307,338, filed 10 June 28, 1919.

Having described my invention what I claim is:

1. In combination a piston having an annular groove, the side walls of which are inclined divergently outward with relation to each other and whose depth is greater than the axial width of its opening, and a split metallic piston ring in said groove, the radial thickness of which is greater than its 15 axial thickness and whose greatest axial thickness is slightly greater than the width of the groove at the periphery of the piston.

2. In combination a piston having an annular groove, the side walls of which are inclined divergently outward with relation to each other, one of which lies substantially in a plane, the depth of the groove being greater than the axial width of its opening, and a split metallic piston ring in said 20 groove, the radial thickness of which is greater than its axial thickness and whose greatest axial thickness is slightly greater than the width of the groove at the periphery of the piston.

3. In combination a piston having an annular groove, the side walls of which are inclined divergently outward with relation to each other, the depth of which is greater than its axial width at the periphery of the 35 metallic piston, and a split piston ring in said groove having its height at its outer periphery greater than the greatest width of the groove and having a radial annular thickness greater than its axial thickness at 40 its outer periphery.

4. In combination a piston having an annular groove, the side walls of which are inclined divergently outward with relation to each other, one side wall lying substantially in a plane, the depth of the groove be-

ing greater than its axial width at the periphery of the piston, and a split metallic piston ring in said groove having its height at its outer periphery greater than the greatest width of the groove and having a radial annular thickness greater than its axial thickness at its outer periphery. 55

5. In combination, a piston having an annular groove, the depth of which is greater than its axial width at the surface of the piston, said groove having a side wall inclined outwardly and away from the pressure exerting fluid chamber, a split metallic piston ring in said groove having a side wall of the same slope as, and corresponding to, the inclined side wall of the groove, said ring being of greater radial width than axial width and of such size relative to the groove that when in place it will protrude beyond the surface of the piston. 60 65 70

6. In combination a piston having an annular groove, the depth of which is greater than its axial width at the surface of the piston, said groove having a side wall inclined outwardly and away from the pressure exerting fluid chamber, a split metallic piston ring in said groove having a side wall of the same slope as, and corresponding to, the inclined side wall of the groove, said ring being of greater radial width than 75 axial width and of such size relative to the groove that when in place it will protrude beyond the surface of the piston and leave a carbon space at the bottom of the groove. 80 85

7. In combination, a piston having an annular groove, said groove having a wall inclined outwardly and away from the working surface of the piston, a split metallic piston ring in the groove, the radial thickness of the ring being greater than its axial thickness and having its opposite faces divergent relative to each other, the sides of the groove having portions which coact with the divergent faces to hold the ring so that 90 95 its outer periphery will be beyond the periphery of the piston.

In testimony whereof I affix my signature.

HARRY B. JOHNSTON.
